CLAIM

The ornamental design for a device holder as shown and described.

DESCRIPTION

FIG. 1 is a front perspective view of a device holder showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another front perspective view showing the device holder is fixed on a board with a device located thereon.

The evenly spaced broken lines in FIGS. 1-9 depict portions of the device holder which form no part of the claimed design. The dot-dash broken lines depict the boundaries of the claimed design and form no part thereof. The board and device shown in evenly spaced broken lines in FIG. 9 depict environmental subject matter and form no part of the claimed design.

1 Claim, 8 Drawing Sheets
